(57) **CLAIM**

The ornamental design for a book display, as shown and described.

DESCRIPTION

FIG. 1 is a perspective view of a book display;
FIG. 2 is a front plan view thereof, the rear view being the same;

FIG. 3 is a first side plan view thereof, the second side being the same;

FIG. 4 is a top plan view thereof;

FIG. 5 is a bottom plan view thereof; and,

FIG. 6 is a perspective view of the book display where an open book is centrally displayed.

Elements shown in broken lines are provided to illustrate an environment of use and form no part of the claimed invention.
